UNITED STATES PATENT OFFICE.

JULIUS E. HEIMERL AND JOHN H. POMMER, OF MILWAUKEE, WISCONSIN, ASSIGNEES
TO STA-HOT LUNCH BOX COMPANY, OF MILWAUKEE, WISCONSIN.

POLISHING MITTEN.

Application filed January 16, 1923. Serial No. 612,914.

To all whom it may concern:

Be it known that we, JULIUS E. HEIMERL and JOHN H. POMMER, both citizens of the United States, and residents of Milwaukee, in the county of Milwaukee and State of Wisconsin, have invented certain new and useful Improvements in Polishing Mittens; and we do hereby declare that the following is a full, clear, and exact description thereof.

10 This invention relates to a polishing device and scouring device and is particularly directed to a polishing mitten or pad.

The use of steel wool for polishing and cleaning purposes has serious drawbacks which prevent its use in a number of places where otherwise it would be employed. For example, the steel wool consists of relatively fine and somewhat brittle, filamentary threads of metal. These are usually held directly in the operator's hand in a sort of a bundle and rubbed against the surface to be polished. Obviously, the operator's hand is frequently damaged and the strands break into small particles, which clog up a sink 20 for instance, or penetrate the operator's hand.

This invention is to overcome the above noted defects and objects of such invention are therefore to provide a polishing device which employs steel wool or other material of a similar nature, freed from the noted defects, to provide a polishing device which may be worn upon or held by the hand of the operator in a manner to protect such operator's hand, without however, in any way detracting from the efficiency of the device, to provide a polishing or scouring device which will retain the broken portions of the strands for further utilization and prevent them from falling in the sink or into 40 undesirable places.

Further objects are to provide a hand mitten or pad which may be constructed in an extremely cheap and simple manner, which is provided with a felted pad composed of fibrous material with the steel wool intermingled therewith, which may be worn upon the operator's hand without damage thereto, which will not turn upon the operator's hand and move out of position, and which 50 gives both the scraping and polishing action of the steel wool and also that of the fibrous material.

An embodiment of the invention is shown in the accompanying drawings, in which:—

Figure 1 is a view from the palm side of the polishing mitten.

Figure 2 is a corresponding view from the rear side thereof.

Figure 3 is an enlarged transverse sectional view on the line 3—3 of Figure 1.

Referring more particularly to the drawings, it will be seen that the polishing mitten consists of an open-end sack which may be formed of canvas for instance, or other suitable protecting flexible material. It may comprise a rear portion 1 and a palm portion 2 which, if desired, may be integral along one edge and may be stitched together as indicated at 3 along the other edge. If desired, the end portions may be turned in as indicated at 4 to provide a finishing edge and a tab consisting of a loop of flexible material as indicated at 5 may be stitched to such inturned edge to provide an eyelet, by means of which the mitten may be hung up.

The palm side of the mitten is provided with a matted or felted pad 6 composed of suitable fibrous material, with steel wool felted or matted therein, as may be clearly seen from Figures 1 and 3. This fibrous material may be of cotton, wool or in fact, any suitable material which will cooperate with the steel wool to form a matted or felted structure and which will retain the steel wool in place when the portions thereof become broken into relatively small members. In actual practice it has been found that cotton batting cooperates well with steel wool to secure the above noted results.

The pad 6 is quilted or stitched to the palm portion of the mitten by means of a plurality of lines of stitching such as indicated at 7 for instance. A line of stitching 8 may be run longitudinally of the mitten part way up from the tip thereof, so as to partially divide the mitten into two compartments, each of which is adapted to receive certain of the fingers of the operator, with the line of stitching positioned between adjacent fingers. This construction will prevent the mitten from turning upon the operator's hand, into an undesirable position.

It is to be particularly noted that both the polishing action of the steel wool and

that of the fibrous material occur simultaneously, when the mitten is in use and a high polish is quickly secured—the steel wool will remove any scale or crust upon the article and will aid in polishing, while the fibrous material will cooperate and give a high polish to the article.

It will thus be seen that a polishing mitten has been provided which employs steel wool in a novel and effective manner without danger to the operator and without danger of the steel wool's breaking into small particles and becoming detached from the pad.

Although one form of the invention has been described in considerable detail, it is to be understood that the invention may be embodied in several different forms and is

therefore to be limited only as set forth in the appended claims.

We claim:

1. A polishing mitten comprising a pocket for the reception of the hand and having front and rear walls, and a matted pad composed of intermingled steel wool and fibrous material.

2. A polishing pad comprising a matted pad of intermingled strands of abrasive material and fibrous material.

In testimony that we claim the foregoing we have hereunto set our hands at Milwaukee, in the county of Milwaukee and State of Wisconsin,

JULIUS E. HEIMERL.
JOHN H. POMMER.
